UNITED STATES PATENT OFFICE.

HERBERT C. DRUMM, OF CANTON, OHIO, ASSIGNOR TO THE UNION METAL MANUFACTURING COMPANY, OF CANTON, OHIO, A CORPORATION OF OHIO.

BOTTOM BOARD FOR FOUNDRY-FLASKS.

1,321,812.

Specification of Letters Patent. Patented Nov. 18, 1919.

Application filed May 8, 1919. Serial No. 294,371.

To all whom it may concern:

Be it known that I, HERBERT C. DRUMM, a citizen of the United States, residing at Canton, in the county of Stark and State of Ohio, have invented a new and useful Bottom Board for Foundry-Flasks, of which the following is a specification.

The invention relates to improvements in bottom boards for foundry flasks and has for its objects the production of a bottom board formed of sheet metal and provided with integral strengthening ribs producing a bottom board which is light and strong; and to generally improve and simplify the construction of bottom boards for foundry flasks.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a perspective view of a bottom board constructed in accordance with the invention, showing the upper face of the board.

Fig. 2 is a perspective view of the under face of the board.

Fig. 3 is a section on the line 3—3, Fig. 2.

A practical embodiment of the invention is disclosed in the accompanying drawings, forming a part of this specification in which similar numerals of reference indicate corresponding parts throughout the several views.

The usual method of making bottom boards for foundry flasks has been to build them out of wood, but owing to the excessive heat and burning gases to which they are subjected, in their use, they are easily destroyed by burning and warping and although attempts have been made to make bottom boards of metal, in order to produce a bottom board which will stand the wear and heat to which they are subjected without warping, the bottom boards thus far pro-

duced of metal have been so heavy and unwieldy that they have not been practical.

The bottom board to which this application pertains is so constructed that it combines lightness with durability, being formed of sheet metal provided with spaced downwardly stamped integral ribs, the top face of the board presenting a substantially flat surface which is necessary for the use to which the board is put. It is well understood that bottom boards must be rigid in order to prevent any springing and owing to the fact that they are handled considerably it is of importance that they be light in weight.

The bottom board is formed of a metal sheet 1 provided with spaced longitudinal, downwardly pressed ribs 2 for the purpose of giving rigidity to the board and preventing longitudinal warping or springing thereof. The longitudinal edges of the board are turned under forming strengthening beads 3 which further tend to strengthen and reinforce the board longitudinally.

Reinforcing bars 4, preferably formed of sheet metal and provided with downwardly disposed ribs 5 are located transversely across the under surface of the board near the ends thereof, being attached to the ribs 2 of the board by means of rivets 6 or their equivalents. These reinforcing bars prevent transverse buckling or warping of the bottom board.

For the purpose of raising the board from the floor and making it easier to handle the same, and allowing room to attach the usual clamps which are used to clamp the mold sections to the bottom board the board is provided with feet 7.

The depressed ribs 2 not only reinforce the bottom board but also act as escapement channels to allow the gases formed by the cores to escape thus preventing accidents and damage to the casting as it is not unusual for cores to explode where these gases cannot escape. It should be noted that similar ribs may be also provided transversely of the bottom board intersecting the longitudinal ribs.

The reinforced edges produced by the forming of the beads 3 provide suitable attaching means for the usual clamps. Apertures 11 are provided at intervals in the body of the bottom board to further allow

escapement of the gases formed from the cores. Feet 7 are provided near the corners of the board, each of these feet comprising a sheet metal strip bent into channel form and provided at its upper edges with the out-turned flanges 8 by means of which it is connected to the body of the bottom board by rivets 9 or their equivalents. Notches 10 are formed in the upper edges of the feet 7 to accommodate the adjacent rib 2 of the bottom board. This construction further strengthens the structure, making the attachment of the feet to the bottom board more rigid as the bars 4 are located within the channels of the feet.

Although the drawings and above specification disclose the best mode in which I have contemplated embodying my invention I desire to be not limited to the details of such disclosure, for in the further practical application of my invention, many changes in form and construction may be made, as circumstances require or experience suggests without departing from the spirit of the invention, within the scope of the appended claims.

I claim—

1. A bottom board for foundry flasks comprising a metal sheet provided with spaced downwardly pressed longitudinal ribs and transversely disposed reinforcing means upon its under surface.

2. A bottom board for foundry flasks comprising a metal sheet provided with spaced downwardly pressed ribs intervening flat portions and angularly disposed reinforcing bars attached to its under surface.

3. A bottom board for foundry flasks comprising a metal sheet provided with spaced, downwardly pressed ribs and intervening flat portions and reinforcing bars located at right angles to the ribs and connected to the under surfaces of the ribs.

4. A bottom board for foundry flasks comprising a metal sheet provided with spaced, downwardly pressed ribs and intervening flat portions, angularly disposed reinforcing means upon its under surface and beads formed upon its edges.

5. A bottom board for foundry flasks com-

prising a metal sheet provided with spaced, downwardly pressed longitudinal ribs and transversely disposed reinforcing bars attached to its under surface.

6. A bottom board for foundry flasks comprising a metal sheet provided with spaced, longitudinal, downwardly pressed ribs and transversely disposed bars connected to said ribs.

7. A bottom board for foundry flasks comprising a metal sheet provided with spaced, longitudinal, downwardly pressed ribs and intervening flat portions.

8. A bottom board for foundry flasks comprising a metal sheet provided with spaced, longitudinal, downwardly pressed ribs and intervening flat portions and integral beads formed upon the edges of the sheet.

9. A bottom board for foundry flasks comprising a metal sheet including spaced, longitudinal, downwardly pressed ribs and intervening flat portions, transversely disposed reinforcing bars connected to said ribs and channel shaped feet connected to the underside of said bottom board, at points where said bars are connected to said ribs.

10. A bottom board for foundry flasks, comprising a metal sheet provided with spaced downwardly pressed longitudinal ribs and transversely disposed reinforcing means.

11. A bottom board for foundry flasks comprising a metal sheet provided with spaced downwardly pressed ribs and intervening flat portions of greater width than the ribs.

12. A bottom board for foundry flasks comprising a metal sheet provided with spaced downwardly pressed ribs and intervening flat portions and reinforcing means upon its under surface.

13. A bottom board for foundry flasks comprising a metal sheet provided with spaced downwardly pressed ribs and intervening flat portions of greater width than the ribs and reinforcing means upon its under surface.

In testimony that I claim the above, I have hereunto subscribed my name.

HERBERT C. DRUMM,
